ADJUSTABLE HOLDER FOR LIP STICKS
AND THE LIKEHoward F. Reichenbach, Waterbury, Conn., as-
signor to The Chase Companies, Incorporated,
Waterbury, Conn., a corporation

Application October 24, 1934, Serial No. 749,734

6 Claims. (Cl. 206—56)

This invention relates to adjustable holders for lipsticks and the like and relates in particular to an improvement in the carrier or so-called "elevator" feature of such holders.

- 5 One of the objects of the present invention is to provide a carrier for lipsticks and the like so constructed as to insure its smooth and reliable movement by an appropriate operating mechanism or device.
- 10 A further object is to provide a carrier combining the foregoing characteristics with capacity for superior grip upon a lipstick or the like to thereby insure the retraction thereof into the holder.
- 15 With the preceding and other objects in view, as will appear to those skilled in the art from the following, considered in conjunction with the accompanying drawing and appended claims, the present invention includes all features disclosed 20 therein which are novel over the prior art.

In the accompanying drawing:

Fig. 1 is a central longitudinal sectional view of an adjustable lipstick holder having incorporated therein a carrier embodying the present invention;

Fig. 2 is a transverse sectional view thereof;

Fig. 3 is a perspective view of the actuating-pin;

Fig. 4 is an underside view of the cup-like carrier or elevator;

Fig. 5 is a view thereof mainly in side elevation and partly in vertical section; and

Fig. 6 is a broken perspective view partly in section of the carrier or elevator.

35 The particular embodiment of the present invention herein chosen for illustration includes a cup-like carrier or elevator 10 preferably drawn up from sheet-metal and comprising an annular side-wall 11 and a bottom wall 12. The bottom 40 wall 12 of the said carrier is pierced and a portion thereof is bent upwardly into a plane parallel with the axis of the carrier to provide a sheet-metal supporting-tongue 13 having its upper end shaped to form an anchoring-prong 14 for embedding into a lipstick or similar article (not shown), when such lipstick or the like is pressed 45 into the open upper end of the carrier 10. About midway of its height, the supporting-tongue 13, which is located near one side of the carrier, is provided with a bearing-opening 15 aligned with a bearing-opening 16 formed in an inset-portion 50 of the side-wall 11 of the carrier.

55 Inserted through the bearing-openings 15 and 16 respectively formed in the supporting-tongue 13 and the side-wall 11 of the carrier 10, is an

actuating-pin 18 comprising a shank 18a having a head 19 at its outer end. The said head 19 is seated in the inset-portion 17 of the side-wall 11, and projects beyond the periphery of the latter for entry into a helical guide-way 20, pierced in 5 the wall of a tubular inner shell 21 mounted with capacity for rotation within a casing 22 formed of molded composition or other suitable material.

The lower end of the inner shell 21 has secured to it, by solder or other suitable means, a peripherally-knurled cap 23, preferably projecting slightly beyond the periphery of the lower end of the casing 22 for being conveniently gripped by the fingers of the user. As before stated, the inner shell 21 is designed for rotative movement 15 with respect to the casing 22, and for the purpose of preventing its endwise displacement, the said inner shell is outstruck near its lower end to provide a retaining-nib 24 turning in an annular retaining-groove 25, formed in the interior of the 20 casing 22 adjacent the lower end thereof.

The head 19 of the actuating-pin 18 is of sufficient length to project and bear not only in the helical guide-way 20 in the inner shell 21, but also in a longitudinal guide-way 26, formed in 25 the interior of the casing 22 and intersecting the annular retaining-groove 25 therein.

Preferably, the shank 18a of the actuating-pin 18 fits the bearing-openings 15 and 16 in the carrier 10 with a free fit, so that the said pin 30 may rotate, and when the inner shell 21 is rotated by means of its knurled cap 23, the carrier 10, together with the lipstick or other article which it may carry, will be moved longitudinally of the casing to project or withdraw a lipstick 35 or the like from the open upper end thereof. A suitable cap (not shown) may be installed upon the contracted upper end of the casing 22 to seal in the contents thereof when the holder is not 40 in use.

By providing the inset-portion 17 in the carrier 10, the head 19 of the actuating-pin 18 is assured of a proper bearing in the guide-way 20 in the inner shell 21, without endangering the jamming of the parts, which might be occasioned 45 by the entry of the thin metal of the shell 21 between the inner face of the head 19 of the actuating-pin 18 and the side-wall 11 of the carrier 10.

It will further be noted that the actuating-pin 18 has ample stability and freedom from jamming 50 by virtue of the relatively-great distance between the bearing-openings 15 and 16, and that, if desired, the upper end of the bearing-tongue 13 may also serve as an anchoring-prong 14 for a 55 lipstick or the like.

The invention may be carried out in other specific ways than that herein set forth without departing from the spirit and essential characteristics of the invention, and the present embodiment is therefore to be considered in all respects as illustrative and not restrictive, and all changes coming within the meaning and equivalency range of the appended claims are intended to be embraced therein.

10 I claim:

1. A substantially-cup-shaped carrier for lipstick holders and the like having one end open and its opposite end provided with an end-wall, and having a perforation in its side-wall and having a tongue bent up from its said end-wall and extending toward the open end of the carrier and provided with a bearing in substantially-lateral registration with the perforation in the side-wall of the carrier; and an actuating-pin 15 inserted in the perforation of the side-wall of the carrier and engaging the bearing in the said tongue and projecting beyond the outer surface of the carrier.
2. A substantially-cup-shaped carrier for lipstick holders and the like having one end open and its opposite end provided with an end-wall, and having a perforation in its side-wall and having a tongue bent up from its said end-wall and extending toward the open end of the carrier and provided with a perforation in substantial 25 lateral registration with the perforation in the side-wall of the carrier; and an actuating-pin inserted in the perforations in the side-wall and in the said tongue of the carrier, and projecting 30 beyond the outer surface of the side-wall thereof.
3. A substantially-cup-shaped carrier for lipstick holders and the like having one end open and its opposite end provided with an end-wall, and having a perforation in its side-wall and having a tongue bent up from its said end-wall and extending toward the open end of the carrier, the said tongue being provided with a bearing in substantial lateral 35 registration with the perforation in the side-wall of the carrier; and an actuating-pin inserted in the perforations respectively formed in the side-wall and in the tongue of the said carrier and projecting 40 outwardly from the said side-wall of the carrier; and an actuating-pin inserted in the perforation in the side-wall of the carrier and engaging with the bearing in the said tongue of the carrier, and having an enlarged head-portion projecting 45 beyond the outer surface of the said side-wall.

4. A substantially-cup-shaped carrier for lipstick holders and the like having one end open and its opposite end provided with an end-wall, and having a perforation in its side-wall and having a tongue bent up from its said end-wall and extending toward the open end of the carrier, the said tongue being provided with a bearing in substantial lateral 5 registration with the perforation in the side-wall of the carrier; and an actuating-pin inserted in the perforation of the side-wall of the carrier and engaging the bearing in the said tongue, and projecting beyond the outer surface of the carrier; the said tongue bent up from the end-wall of the said carrier extending above the said actuating-pin, and providing 10 an anchor for engagement with a lipstick or the like.

5. A substantially-cup-shaped carrier for lipstick holders or the like having one end open and its opposite end provided with an end-wall, and having its side-wall inset and pierced to form a bearing-opening, and having a tongue bent up from its said end-wall and extending toward the open end of the carrier, the said tongue being provided with a bearing in substantial lateral 20 registration with the perforation in the side-wall of the carrier; and an actuating-pin inserted in the perforation in the side-wall of the carrier and engaging with the bearing in the tongue thereof, and provided with a head-portion 25 projecting outwardly from the said inset-portion of the side-wall of the carrier.

6. A substantially-cup-shaped carrier for lipstick holders or the like having one end open and its opposite end provided with an end-wall, and having its side-wall inset and pierced to form a bearing-opening, and having a tongue bent up from its said end-wall and extending toward the open end of the carrier, the said tongue being provided with a perforation in substantial lateral 35 registration with the perforation in the side-wall of the carrier; and an actuating-pin inserted in the perforations respectively formed in the side-wall and in the tongue of the said carrier and projecting 40 outwardly from the said inset-portion of the side-wall of the carrier.

HOWARD F. REICHENBACH.
